UNITED STATES PATENT OFFICE.

FREDERICK WILLIAM ROWBOTTOM, OF RANIER, MINNESOTA.

GAS-ENGINE STARTING DEVICE.

1,284,461.

Specification of Letters Patent. Patented Nov. 12, 1918.

Application filed January 19, 1918. Serial No. 212,721.

To all whom it may concern:

Be it known that I, FREDERICK W. Rowbottom, a citizen of the United States, residing at Ranier, in the county of Koochiching and State of Minnesota, have invented new and useful Improvements in Gas-Engine Starting Devices, of which the following is a specification.

This invention relates to a starting device for a gas engine, and the object is to provide manually operated means of improved construction for use on engines of large capacity for producing the initial explosion after the engine has been primed and the charge has been compressed.

The invention consists in providing manually operated means of novel construction acting in conjunction with the automatically operating ignition devices of substantially the form now employed.

In the drawings:

Figure 1 is a view in elevation showing the device applied to an engine cylinder.

Fig. 2 is a top plan view of the construction shown in Fig. 1.

Figs. 3 and 4 are detached views in perspective of certain elements of the device, described below.

Fig. 5 is a section through the mounting and guiding means for the reciprocable bar, the bar being shown in Fig. 3 and a portion of the guiding means in Fig. 4.

Fig. 6 is a perspective view showing a portion of the contact making mechanism controlled by a trigger mounted on an arm of the reciprocable bar.

Referring to the drawings in detail, a cylinder is designated 10 and the oscillating arm controlling the operation of the ignition mechanism in the well known manner is shown at 14 being mounted at 15. One side of a circuit is designated 16 and leads from a battery 17 through any suitable insulating connection 20. This arm 14 carries a pivotally mounted latch member or the like designated 21 coöperating with a trigger described below and constituting a part of the construction on which the present application is based.

A hand lever 25 is pivotally mounted at 26 and has pivotal connection at 27 with a bar 28 slotted longitudinally as shown at 29. This slotted portion is engaged by a roller 30 carried on a bolt or the like 31 having an elongated head 32 and is provided with a nut 33 on the opposite end. The roller 30

provides for the free movement of the bar 28 and acts as a guiding member. The bolt 31 is mounted in a box 34 having about the proportions shown and being secured in any suitable manner. The head 32 of the bolt passes through a slot 35 in the box and is given a quarter turn for the purpose of producing proper engagement.

A bar 28 carries a frame or the like designated 37, the frame being secured by means of bolts 38, and including an arm 39 having a beveled end 40, and a plurality of fork members 42 extending parallelly and serving to pivotally mount a trigger 44 which is under the control of a coiled spring 45. This trigger includes an offset or hook portion 46, and an offset portion 47 constituting a stop.

The oscillating member constituting a portion of the contact making mechanism is designated 48 and includes a plurality of arms 49 and 50, arm 49 being connected with a coiled spring 51, and the opposite arm being engaged by the trigger 44 when the engine is to be started by the operation of the ignition device.

In starting the engine after the latter has been primed and after compression has been secured, and the switch (not shown) controlling the electric circuit has been thrown in, the lever 25 is operated, the trigger 44 being in the position shown in Fig. 2, and arm 50 of the ignition mechanism is operated for producing a spark for the initial explosion. It will be understood that arm 28 is returned to operative position, with the trigger 44 on the proper side of arm 50 to effect the operation thereof, this return movement of bar 28 being permitted in view of the pivotal and resilient mounting of trigger 44. Should the beveled end 40 accidentally come into engagement, it will only be a slight engagement and will not prevent the required movement of the elements.

What is claimed is:

1. In a device of the class described, the combination with an oscillating element forming a portion of the ignition mechanism of a gas engine, means for operating said oscillating member, and additional means engaging and operating the oscillating member for producing the initial explosion, said means last mentioned comprising a reciprocable bar, and a pivotally and resiliently mounted trigger carried thereby.
2. In a device of the class described, a re-

ciprocable bar, means for guiding the movement of the latter, a pivotally mounted lever for operating the bar, a pivotally and resiliently mounted trigger carried by the bar,
5 an oscillating member comprising an element of the ignition mechanism of a gas engine, said trigger engaging the oscillating element, and means for engaging said oscillating member during the continued opera-
10 tion of the engine.

3. In a device of the class described, a reciprocable bar slotted longitudinally, means for operating said bar, a frame carried by the bar and including a longitudi-

nally extending arm at one side of the 15 frame, a plurality of longitudinally extending arms at the other side of the frame, a trigger pivotally and resiliently mounted between the arms last named, an oscillating member comprising an element of the igni- 20 tion mechanism of a gas engine, said member being engaged by the trigger to produce the explosion of the initial charge, and means for engaging the oscillating member during the continued operation of the en- 25 gine.

In testimony whereof I affix my signature.
FREDERICK WILLIAM ROWBOTTOM.
